United States Patent Office

Des. 231,625
Patented May 7, 1974

231,625

GOLF PUTTER

Frank D. Werner, Box SR9, Jackson, Wyo. 83001

Filed Sept. 15, 1972, Ser. No. 289,422

Term of patent 14 years

Int. Cl. D21—02

U.S. Cl. D34—5 CB

FIG. 2

FIG. 2

FIG. 3

FIG. 4

FIG. 5

FIG. 6

FIG. 7

FIG. 8

FIG. 1 is a top perspective view of a golf putter embodying my new design;

FIG. 2 is a front elevational view of the putter head embodying my new design;

FIG. 3 is a top plan view thereof;

FIG. 4 is a rear elevational view thereof;

FIG. 5 is a side view thereof;

FIG. 6 is a bottom view thereof;

FIG. 7 is a sectional view thereof taken as on line 7-7 in FIG. 5; and

FIG. 8 is a sectional view thereof taken as on line 8-8 in FIG. 6.

I claim:
The ornamental design for a golf putter, substantially as shown.
